Primary Examiner — Karen S Acker*Assistant Examiner* — Wendy L Arminio(74) *Attorney, Agent, or Firm* — Thomas C. Feix(57) **CLAIM**

The ornamental design for a plastic film with surface pattern, as shown and described.

DESCRIPTION

The sole FIGURE is a top plan view of a plastic film with surface pattern showing our new design.

The broken lines shown along the border of the plastic film with surface pattern depict the boundaries of the claimed design and form no part thereof.

1 Claim, 1 Drawing Sheet(56)
